PAINT STRIPER GUIDE

Karl V. Eklov, Detroit, Mich.

Original application July 29, 1932, Serial No. 625,741. Divided and this application July 12, 1933, Serial No. 680,049

7 Claims. (Cl. 33—42)

This application is a division of my former application Serial No. 625,741, filed July 29, 1932, and relates to the guide unit, with modifications, as used thereon.

5 The object of my invention is to produce an adjustable guide adapted for use with any type of paint striping device, designed for engaging guiding edges or projections for directing the path of the striping unit with which it is used, for producing uniformly spaced stripe lines thereon.

Another object is to produce a paint striping guide unit that may be readily adjusted and adapted to engage different kinds and types 15 of guiding edges for applying the striping device therealong.

A further object is to produce an automatic adjusting guide unit, adaptable to any paint striping unit, and operative with some of the 20 connected striping elements.

A still further object is to produce a paint striping guide that is simple in construction, easily and efficiently operated and can be manufactured at a very low cost.

25 These several objects are attained by the construction and arrangement of parts more fully hereinafter set forth.

Similar parts on all drawings are marked by 30 similar numerals or letters.

Fig. 1 is a plan view of one form of my guide as illustrated in the former application of which this is a division thereof, showing the guide frame with the guide arms mounted thereon and the adjusting means.

35 Fig. 2 is a side view of my former striping device with the guide unit mounted thereon, showing the relative positions of the operating parts to the striping unit disc.

40 Fig. 3 is a plan view of a slightly modified type of guide frame adapted for the universal type of striping unit and which is set forth in my patent application Ser. No. 675,584, filed June 13, 1933, showing the adjustable guide frame and 45 adjusting means movably mounted on a supporting thimble.

Fig. 4 is a side view of the guide frame as mounted on the above mentioned universal type of striping unit showing the relative position of 50 the various guide units to the striping unit disc.

Fig. 5 is a side view of a modified form of 55 guide frame, showing a distorted frame plate with angularly positioned guide arms mounted thereon.

55 Fig. 6 is a plan view of the guide frame plate

showing the arrangement of the guide arms mounted thereon.

Fig. 7 is a side view of a further modified form of guide frame showing the application of different types of guide arm means. 5

Fig. 8 is the plan view of the guide frame as shown in Fig. 7 showing the relative positions and general arrangement of the operating parts.

Fig. 9 is a side view of an alternate form of guide frame having adjustable, hinged guide arm 10 and showing the opened and closed positions of each.

Fig. 10 is a plan view of the hinged guide frame showing the relative position of the operating parts and the spring means for retaining the 15 guide arms in a closed position on the guide frame.

In general my device comprises an adjustable frame suitable for slidably mounting over an elongated striping nib unit, and may be mounted directly thereon or by a special guide thimble, the frame carriers mounted thereon, either fixedly or adjustably, roller or ball tipped guide arms, and preferably provided with some adjusting means 20 therein for compensating for irregular surface 25 formations over which the striping is to be applied.

My invention may be best understood when described in combination with the paint striping unit with which it is to be used. 30

I will now describe more fully the detailed construction of my adjustable paint striping guide, referring to the drawings and the marks thereon.

The preferred type of guide frame is set forth 35 in the Figs. 3 and 4 of the drawings, showing the guide as adapted to the universal type of striping unit, although it is equally as adaptable to other types of striping units such as is illustrated in the Figs. 1 and 2 of the drawings, and which type is more fully described in my patent application Ser. No. 625,741, filed July 29, 1932 as heretofore referred to, this application being a division thereof. 40

The universal type of striping unit as illustrated in the Figs. 3 and 4, comprises an elongated striping nib 1 having the body formed of successively stepped cylindrical sections *a*, *b*, *c*, and *d*, all concentric about the same axis, and having a small, pinned surface striping disc 2 rotatably mounted in one end thereof, said disc being partially enclosed by a curved spring member 3, the body section being provided with a central paint channel *e* lengthwise thereof leading to the said striping disc. The cylindrical end section *a* of the nib body is formed with an annular groove recess 50

4 and ports 5 opening into the central paint passage e, and carries rotatably mounted thereon a mounting collar 6 and attached paint container 7, the combined sections being capable of a complete rotation about the nib end, and is formed with a paint passage channel 8 leading from the container 7 through the collar walls and opening into the annular groove 4 of the nib end, providing a continuous paint passage from the container to the striping disc 2. A control valve 9 formed with a port 10 is slidably mounted through the collar 6, intercepting the paint passage 8, for opening and closing said channel as the valve 9 is displaced endwise therethrough, said valve 9 being formed with an engaging groove 11 at the outer end thereof. Slidably mounted over the nib body sections b, c, and d is a shouldered cylindrical guide thimble 12 formed with an end flange collar 13, said collar 13 positioned to engage the valve end groove 11 of the control valve 9, for moving said valve simultaneously therewith and allowing complete rotation thereof about the thimble axis without disconnecting the valve therefrom. A compression coil spring 13 is mounted between the guide thimble 12 and the nib body 1, engaging their respective shouldered ends, displacing said thimble 12 to a position adjacent the mounting collar 6, likewise displacing the connected control valve 9 therewith and closing the paint passage channel 8 leading to the striping nib 1. Mounted over the guide thimble 12, at right angles thereto, is a guide frame 14, preferably slidably mounted thereon and splined thereto, having a clamping screw 15 mounted therethrough and provided with a lock nut 16 for rigidly clamping said frame in any desired adjusted position on the thimble. When desired, the frame 14 may be fixedly mounted on the thimble 12, either by a pressed fit or by any other means which will rigidly retain the frame thereon. An arm block 17 is slidably mounted on the under side of the frame 14 by means of rigid slide rods 18 which are positioned to slide through the frame slide recesses, and are clamped therein at any adjusted position by the head of the screw 15 and the nut 16, the adjustment of said arm block 17 being always at right angles to the axis of the nib body 1. Guide arms 19 formed of rigid metal posts are fixedly mounted in the arm block 17, and preferably provided with ball tipped ends formed of a contact ball 20 and the small bearing ball 21 mounted therebeneath, although any type of sliding or rolling end contact will operate, and should be selected and adopted as the guide rib or template with which it is to be operated may require. The purpose of the guide unit is two-fold; primarily to engage a guiding rib f or similar template edge, for directing the line of travel of the striping device disc 2 along a predetermined path over the surface to be striped, and, secondarily, when applied to the universal type of striper, it provides operating means for the paint channel control valve for automatically opening and closing same, and also adjustable means for allowing the nib body and striping disc to vary with any surface irregularities over which the striper is passed without disengaging the guide arms from the controlling rib or template edges.

When the guide frame 14 is mounted on the thimble 12 and properly adjusted thereon, the paint control valve 9 being in a closed position over the paint passage, the guide arm tips are positioned slightly back of the striping disc edge, as indicated in the Fig. 4 of the drawings, the operator holding the striper unit in his finger

tips by grasping same on opposite edges of the frame 14, and then applying sufficient pressure thereto when said disc 2 is placed against the painted surface g, displacing the striper nib body 1 by pushing same lengthwise within the thimble 5 section 12, and until the guide arm tips contact the surface g or the rib or template edge, and which displacement also displaces the control valve 9 allowing the paint from the container 7 to flow directly to the striping disc 2 for making 10 the desired stripe line on the painted surface g as the striper is moved thereover.

When my striper guide is to be used with the fixed type of striping device as illustrated in Figs. 1 and 2 of the drawings, the guide thimble 12 is 15 omitted and the frame 14a mounted directly over the cylindrical casing end h of the striper body 22, and clamped thereon in its adjusted position with the respective guide arms positioned slightly back of the surface g' as in the former case. The 20 nib body 1a being slidably mounted within the end casing h and is splined thereto, may be displaced lengthwise therein against the retaining spring 23 by applying pressure to the nib disc 2a as in the former case heretofore described, the 25 operation being also the same.

The guide frame as shown in Figs. 1 and 2 is the same in general arrangement and principle as that illustrated in the Figs. 3 and 4, although the mechanical details are slightly simplified in 30 design, the frame being provided with an ordinary set screw 24, also with a supplemental guide arm 25 on the top side thereof which may be used as a special guide member, or removed as 35 desired.

A modified form of my guide is illustrated in Figs. 5 and 6, showing a solid, but angularly shaped guide frame 14b, fixedly mounted on a cylindrical guide thimble 12b, either by a pressed fit thereon or by a set screw 26, and is provided 40 with variously positioned ball tipped guide arms 19b fixedly mounted therein, each set being positioned to engage a different type or kind of guiding rib or template edge, and making the striping device adapted to two operations on differently ribbed surfaces or template guide edges, and without changing or adjusting the guide frame. The size, shape, type and position of any or all of the various guide arms may be varied and changed as required for engaging and 50 operating with different types or styles of rib or template edges, depending upon the condition under which the striping device is used.

Figs. 7 and 8 illustrate a further modified form of my guide, being formed of a solid, flat guide 55 frame block 14c with a central cylindrical opening for fixedly, or adjustably, mounting on the guide thimble 12c, and is provided with two types of guide members as an illustration of applying different kinds of guide members on the same 60 frame, i. e., the ball tipped guide arms 19c and the rotatably mounted guide rollers 27, the different sets or types being mounted on opposite sides of the frame 14c, each being designed and positioned to engage a different type or shape 65 rib or template edge, also making the striping device adaptable to different striping gages and templates without adjusting the guide frame the same as in the former case.

The Figs. 9 and 10 illustrate a further modification of the frame or guide unit shown in the Figs. 7 and 8, by mounting the special guide arm members 19c and 27 on separated arm blocks 28 and 29 but in the same manner as before, and hingedly attaching same to the guide frame 14d 75

on opposite sides thereof by hinge pins 30, the frame 14d being fixedly, or adjustably, mounted on the thimble 12d as in the former case. The arm blocks 28 and 29 when either, or both are closed in the guide frame 14d occupy exactly the same position as in the Fig. 7, and are retained in that position by a double hook spring bar 31 mounted within the side groove k and retained therein by the pin 32, the hook ends m and n engaging the blocks 28 and 29 respectively retaining them rigidly in the closed positions, or when disengaged therefrom, either at one or both ends will allow either block 28 or 29 to be opened to a position as shown by the dotted lines in the Fig. 9 of the drawings, removing the guide member when not in use and which might obstruct the movement of the striper if projecting objects on the painted surface were positioned in line therewith. The operation is the same as in the former case.

It is apparent that my device is subject to various modifications in both design and detail arrangement of the various elements and units of which it is comprised and without departing from the spirit of my invention, and I claim not only the designs as herein illustrated but all modifications thereof that is substantially a substitution of parts or units herein shown.

Having fully described my paint striper guide what I claim as my invention and desire to secure by Letters Patent is:

1. An adjustable guide unit adapted for a paint striping device and used in combination therewith, comprising a rigid frame formed with an inner opening at right angles therethrough suitable for adjustably mounting over the end of a paint striping device and connect therewith, engaging template guide members mounted thereon and projected beyond the outer face of said frame at approximately right angles thereto and provided with guide rib engaging members.

2. An adjustable guide unit adapted for a paint striping device and used in combination therewith, comprising a frame formed with a central cylindrical opening at right angles therethrough suitable for mounting over the end of a paint striping unit, adjustable thereon, an arm block adjustably mounted on one edge of said frame, and engaging template guide members mounted on the outer face of the arm block.

3. An adjustable guide unit adapted for a paint striper device and used in combination therewith, comprising a frame having a thimble collar mounted at right angles therethrough suitable for slidably mounting over the end of a paint striping device and connect therewith, an ad-

justable arm block formed with parallel slide members slidably mounted on one side of said frame, movable in a direction at right angles to the axis of the frame thimble, engaging template guide members mounted on the outer face of the arm block, and means for retaining said arm block in any adjusted position on the frame.

4. An adjustable guide unit adapted for a paint striper device and used in combination therewith, comprising a frame formed with a flanged, tubular thimble casing at right angles therethrough, suitable for slidably mounting over the end of a paint striping device and connected thereto by splined means, and engaging template guide members mounted on the outer face of said frame.

5. An adjustable guide unit adapted for a paint striper device and used in combination therewith, comprising a frame formed with a recess opening at right angles therethrough, a flanged thimble slidably mounted through said frame recess opening and splined thereto, an arm block formed with parallel slide members slidably mounted on one edge of the frame, and engaging template guide members mounted on the outer face of said arm block.

6. An adjustable guide unit adapted for a paint striping device and used in combination therewith, comprising a cylindrical flanged end thimble formed with an internal spring engaging rib, suitable for slidably mounting over the end of a paint striping device and connect thereto by splined means, a frame formed with a central cylindrical hole at right angles therethrough slidably mounted over the flanged cylindrical thimble and splined thereto, an arm block formed with parallel slide members slidably mounted on one edge of said frame and adjustable thereon in a direction at right angles to the axis of the inclosed thimble, means mounted on the frame for locking the arm block in any adjusted position thereon, and engaging template guide members having rolling contact engaging tips mounted on the outer face of the arm block.

7. An adjustable guide unit adapted for a paint striping device and used in combination therewith, comprising a frame having a flanged tubular thimble casing centrally mounted at right angles therethrough suitable for slidably mounting over the end of a paint striping device and connect thereto by splined means, engaging template guide members hingedly mounted on the edges of said frame and projected from the outer face of said frame, and means for retaining said hinged guide members in predetermined positions.

KARL V. EKLOV. 55
